UNITED STATES PATENT OFFICE.

JOHN G. KJELLGREN, OF CLEVELAND, OHIO, ASSIGNOR TO THE ELECTRIC RAILWAY IMPROVEMENT CO., OF CLEVELAND, OHIO, A CORPORATION OF OHIO.

RHEOSTAT.

1,404,125.

Specification of Letters Patent. Patented Jan. 17, 1922.

Application filed November 13, 1919. Serial No. 337,646.

To all whom it may concern:

Be it known that I, JOHN G. KJELLGREN, a subject of the King of Sweden, and residing at Cleveland, in the county of Cuyahoga 5 and State of Ohio, have invented certain new and useful Improvements in Rheostats, of which the following is a specification.

My invention relates to rheostats, and particularly to rheostats of the general type 10 shown in my co-pending application Serial No. 140,953, filed January 6, 1917, the object of my invention being to provide a single and rugged construction adapted for out of door service, and improved in certain features hereinafter described or shown 15 in the accompanying drawings in which—

Fig. 1 is a side elevation of a rheostat in which my invention is embodied in one form;

20 Fig. 2 is a plan thereof;

Fig. 3 is an end elevation thereof;

Fig. 4 is a transverse section on the line 4—4 of Fig. 1;

Fig. 5 is a diagram of the wiring system;

25 Fig. 6 is an enlarged section through one of the insulated cross bars drawn to an enlarged scale;

Fig. 7 is a partial section through one of the bus bars and its terminal receptacle;

30 Fig. 8 is a horizontal section through a bus bar and its connection terminal;

Fig. 9 is a transverse section through a bus bar showing the connection of a resistance coil thereto; and

35 Fig. 10 is an enlarged side elevation of one of the terminal receptacles and its door.

In the embodiment of my invention here illustrated, my improved rheostat comprises a skeleton frame, the angle iron end posts

40 10 of which are united on each side by three vertically spaced longitudinal channels 11. Extending between the channels are staggered cross bars 12, which serve as guides and insulating supports for the group of

45 parallel resistance wire coils 13. The latter pass in zigzag arrangement from one end of the frame to the other, being engaged with each cross bar 12 as it passes. The current enters the rheostat through a main

50 switch 14, which may be mounted in any suitable position upon the frame, here shown on the top, and is led by conductors passing through the insulating sheath 15 (Fig. 2) to a bus bar 16 arranged at one

end of the frame. On this bus bar are the 55 terminals 17 of a group of distributing switches 18 interposed between certain of the resistance wires and the bus 16. At the opposite end of the frame are several bus bars 19 and 20, 21 and 22, spaced longitudinally apart beneath the frame and connected at spaced intervals to the resistance wires. Plug receptacles 23 associated with the bus bars afford convenient means for connecting the lead (not shown), 60 through which the current is tapped off from the rheostat to the point of use. An auxiliary bus bar 24 may be arranged in like position at the switch end of the frame and connected to one of the buses at the 65 opposite end. The bus 22 is here shown connected to the bus 24. The receptacle 23 for the bus 24 thus affords an auxiliary tapping point of like capacity as that of the bus 22. In the present case the full 70 resistance of the rheostat is interposed between the entrance bus 16 and the tap bus 22, so that the latter and the bus 24, which is tied to it, take the lowest possible current 75 from the rheostat.

When the rheostat is to be used on a track, as for example when it is used in connection with electric welding apparatus for rail bending, it may be mounted through its corner posts 10 on the axle rods 25. The latter 80 are angled up at their inner ends and riveted to the channel 11, while at their outer ends they are laterally extended horizontally to form bearings for the running wheels 26. Any other suitable means may be utilized to 85 expedite the transport of the rheostat from place to place, it being a simple matter, in any type of wheel construction, to secure the supporting wheels to the frame of the rheostat without requiring an additional frame 90 for the running gear. Preferably there are also provided extensible handle bars 27 of U shape at each end of the frame, by means of which the apparatus may be bodily lifted and carried from place to place. In order 95 not to interfere with the track signal circuit, I have here shown the wheels 26 at one end of the frame insulated by bushings 28 (Fig. 1) from the axle rods, while those at the other end serve to ground the frame as a 100 matter of precaution and protection for the operators. Chests or other casings 29 may be mounted at the ends of the frame close 105

above the wheels to receive working tools of one sort or another. The sides and top of the frame are preferably covered by a coarse wire netting 30, which prevents accidental contact with the rheostat coils without interfering with the free circulation of cooling air through the apparatus.

Among the features of construction to which detail attention may be drawn, is that 10 of the cross bars 12 which support the resistance coils. Under operating conditions the wires become practically white hot and necessitate an insulating covering of special character for the cross bars 12 to which they 15 are attached. To meet this situation, the steel tubing 31 (Fig. 6) which forms the core of each cross bar, is first encased in a mica tube 32 of high insulating capacity. This is protected against heat by a wrap- 20 ping 33 of asbestos tape. To bind and waterproof the latter, as well as to prevent shedding of mica scales, I then apply an insulating cement 34. The resistance wires 18 are then attached to the cross bars, for 25 example by wrapping the wire around the bars (one full turn at the mid bar, and approximately one and three quarter turns at the top and bottom bars), or by narrow clamps on the rods, whereupon a further 30 covering 35 of fire-proof, moisture-proof insulating cement is applied which embeds the wire fastening. By passing a heavy current through the rheostat the cement is baked hard and forms a waterproofing dielectric 35 covering which holds all the elements of the insulating covering together rigidly and prevents deterioration. It is to be borne in mind that the present rheostat is designed to operate out of doors, and under practically 40 all weather conditions. Consequently the insulating problem is quite difficult, particularly when utilizing, as the resistance element, high temperature resistance wires. Asbestos is a good insulator against both 45 heat and electricity, but it is somewhat hygroscopic, and will not do for outside work unless protected against moisture. Mica is perhaps the best non-conductor of electricity, but must be protected against 50 the burning out of the binder which holds the mica scales in place. The present construction is one which is not only mechanically strong, but affords excellent insulation under the most trying conditions.

55 When the voltage to be controlled is not very high, the insulated cross bars may be mounted directly in the channels 11. But when the voltage is high, I prefer to make the holes in the channels sufficiently large to 60 space the same from the cross bars which pass therethrough. In such cases strips of heavy insulation 36 are secured in the bottoms of the channels and are pierced to receive and closely engage the ends of the 65 cross bars. The latter are thus mounted in

an insulating support of sufficient mechanical strength.

The distributing switches 18 are mounted on a common insulating base 37 backed by a sheet of asbestos 38, for heat protection. 70 Air spaced from the latter is a screen 39 of asbestos board, which still further protects the switches from the heat of the rheostat as well as affording a channel for air cooling. 75 As explained in my application above mentioned, the resistance coils are of high temperature, non-corrosive wire and are operated at exceedingly high temperatures, so that protection of the switch against their radiant heat is a practical necessity. The 80 distribution of the current by the switches may be varied as desired. Some of the wires are connected to the entrance bus bar 16, others through the switches. If preferred all may be connected through the switches, 85 and in such case one switch may control a group of wires. By the use of distributing switches of this character, and a group of connection bus bars, to any one of which the working lead may be shifted to compensate 90 a drop in the line voltage, a practically constant current may be maintained at the operating tool.

The receptacles 23 (Fig. 7) for the connecting block of the lead are shown located 95 below the bottom longitudinal channel 11, although they may be placed elsewhere if desired. The jack contact 40 is formed from a brass rod slotted at one end to receive the bus bar to which it is riveted at 41. The 100 jack end of the rod is counterbored at 42 and slotted to form spring fingers 43, which insure a good wiping contact with the plug of the lead wire. These jacks, which are arranged at each end of each bus bar, pass 105 through insulating material which serves to separate both the jack rods and the bus bar. For insulation I prefer to use a block 44 of mechanically strong material, such as "formica" fiber and protected against heat by a 110 block 45 of asbestos material which is relatively weak mechanically. A casing 46 surrounding the jack, but separated therefrom by an insulating bushing 47, is provided to prevent accidental contact with the jack. To afford additional support for the insulations 44 and 45 I provide a light angle iron 48 at the lower margin of the insulating blocks, which is attached to the corner angle 10 at one end and supported at its other end by a downward extension of the truss strap 49 (Fig. 1) of the frame. 115

The manner in which the resistance wires are connected to the bus bars may be variously modified, but I have shown a simple 125 construction in Fig. 9. The bar is pierced adjacent its upper edge to receive a series of clamping bolts 50, and the wire is looped beneath the head of the bolt on one side of the bar, carried over the top of the latter, and 130

down on the other side, where it is wrapped on the bolt beneath the nut so that on screwing up the latter the wire is securely clamped in good electrical connection to the bar.

5 To prevent accidental connection to the rheostat at taps of low resistance, I provide covers 51 (Fig. 10) over the taps of the bus bars 19, 20 and 21, but leave exposed the taps for the bus bars 22 and 24. While these covers are pivoted and may be raised to obtain access to the taps for the bars 19, 20 and 21, the operator is nevertheless warned thereby that he is plugging into a relatively high current and is automatically guided into the 15 open taps of the bars 22 and 24. This is a feature of considerable practical value, especially in work around mines where unskilled operators are common and there is considerable danger of serious injury not 20 only to the operator, but to the rheostat and the working tool by taking excess current from the rheostat.

It will be noted as a feature of convenience that the main switch 14 may be operated 25 from both sides of the frame, and that the current tap jacks are arranged at each end of each of the bus bars for the same reason. The screens 52 extending above the frame on opposite sides of the main entrance switch 30 protect the latter against mechanical injury, while a sheet of asbestos board 53 is provided upon which the switch rests, and by which it is protected from the heat of the rheostat.

The construction illustrated may be varied 35 in detail without departing from what I claim as my invention.

I claim—

1. A rheostat comprising longitudinally 40 extending side members of structural metal, strips of mechanically strong insulation carried by said side members, and cross bars for its resistance wires, said cross bars passing with clearance through said metal side members and being supported in said insulation.

2. A rheostat comprising longitudinal 50 side channels, insulation secured in the bottoms of said channels and cross bars for the resistance wires, said cross bars passing with clearance through said channels and being supported in the insulation secured therein.

3. A rheostat comprising an open-work frame, a series of transverse insulating bars 55 arranged in staggered relation in said frame, a group of resistance wires supported in zigzag position on said transverse bars and insulated thereby from each other and from said bars, a group of bus bars connected to said resistance wires at spaced intervals, and means associated with such bus bar for tapping off the current passing through the rheostat.

4. A rheostat comprising an open-work 65 frame of generally rectangular, elongated

shape, a series of resistance wires arranged zigzag lengthwise of the frame, a group of switches at one end of the frame controlling the distribution of current through the resistance wires, and a group of bus bars arranged toward the opposite end of the frame and connected at spaced intervals to the resistance wires, and terminal means associated with said bus bars to facilitate tapping off the current passing through the 75 rheostat.

5. A rheostat comprising a series of insulating cross bars, a group of resistance wires supported by said insulating bars, and insulated thereby from each other, in combination with a group of bus bars pierced to receive a series of securing screws corresponding to the series of resistance wires, each of said wires being secured to said bus bar by an independent securing screw, and being 85 carried therefrom to a succeeding insulating cross bar, substantially as described.

6. In a rheostat, a bar for supporting the resistance wires, said bar comprising a metal tube, an insulating sheath surrounding the 90 same, and an outer insulating cement of heat-resistance water-proofing material.

7. In a rheostat, a bar for supporting the resistance wires, said bar comprising a metal tube, an insulating sheath surrounding the 95 same, and an outer insulating cement of heat-resistance water-proofing material, the resistance wires being embedded in said cement.

8. In a rheostat, a bar for supporting the 100 resistance wires, said bar comprising a metal tubing with insulating sheath, said sheath having an inner layer of mica, a superposed layer of asbestos, and a heat-resistant, moisture-proof outer cement of 105 insulating material in which the wires are embedded.

9. In a rheostat, a group of resistance wires arranged zigzag in parallel, and isolated from each other, switch means for distributing the current to the resistance wires, and a group of bus bars connected at spaced intervals to the resistance wire group, and independent tap terminals offset from but mechanically and electrically connected to 115 said bus bars to facilitate tapping off current therefrom.

10. In a rheostat, a frame, a group of resistance wires supported therein, switch means arranged at one end of the frame for 120 distributing the current to the resistance wires, said switch means comprising an insulating base mounted in substantially vertical position on the frame, and a screen of heat-insulating material spaced from the base 125 and interposed between the latter and the resistance wires to afford an air cooling channel for the switch base.

11. In a rheostat, a group of tap outlets of different current capacity, and covers for 130

the outlets of greater capacity, the outlet of heat capacity being exposed for unobstructed connection thereto.

12. In a rheostat, a frame, track wheels supported thereon, the wheel at one end of the frame being insulated therefrom to prevent interference with a track signal cir-

cuit, while the wheels at the other end of the frame are electrically connected thereto to ground the same.

10 In testimony whereof I have signed my name to this specification.

JOHN G. KJELLGREN.
